UNITED STATES PATENT OFFICE.

CLARENCE J. DAWSON, OF DETROIT, MICHIGAN, ASSIGNOR TO MOSES E. BLOOM, OF NEW YORK, N. Y.

MEANS FOR PREVENTING THE ACCIDENTAL TAKING OF POISON-TABLETS.

1,174,695.

Specification of Letters Patent.

Patented Mar. 7, 1916.

Application filed July 22, 1914. Serial No. 852,451.

To all whom it may concern:

Be it known that I, CLARENCE J. DAWSON, a citizen of the United States, residing at Detroit, in the county of Wayne and State 5 of Michigan, have invented new and useful Improvements in Means for Preventing the Accidental Taking of Poison-Tablets, of which the following is a specification.

An object of the invention is to provide

- 10 a guard for use in connection with poison tablets and the like, and adapted to prevent the accidental taking of a tablet, particularly by persons endeavoring to take medicine during the night season or in darkened rooms and in which instance they are liable to make mistakes and take poison tablets instead of others which they intended to take.

The invention contemplates, among other

- 20 features, the provision of a guard which is adapted to be applied to the tablet and substantially surround the same so as to prevent the taking of a poison tablet by a person who would otherwise, particularly 25 in cases where a room is darkened or in the night season, take a tablet from a box and simply by the feel or shape of the tablet would conclude that the same is not of a poisonous nature and is the tablet that the 30 person desires to take, whereas in fact the tablet might be of a poisonous nature, thus resulting fatally.

To this end the guard consists of a single piece of material bent to secure the tablet 35 and surround the same, with a series of prongs projecting from the guard and preferably integrally united therewith and which will prick the fingers of the person desiring to take the medicine, thus notifying the 40 person that the particular tablet is a poison one.

The device also contemplates a means whereby a tablet surrounded by the guard can be dropped into a tumbler of water and 45 dissolved without the necessity of removing the guard, whereas if the tablet is to be taken internally in a solid form the guard must first be removed from the tablet.

In the further disclosure of the invention 50 reference is to be had to the accompanying drawings, constituting a part of this specification, in which similar characters of reference denote corresponding parts in all the views, and in which:

Figure 1 is a perspective view showing 55 the guard applied to a tablet, looking at the upper side thereof; Fig. 2 is a similar perspective view looking at the under side of the guard; Fig. 3 is a sectional view taken through the tablet and the guard; and Fig. 60 4 is a view of the blank from which the guard is formed.

Referring more particularly to the views, I disclose a tablet 10 and which, being of a poisonous nature, preferably has the word 65 "Poison" suitably inscribed or molded thereon. In order to prevent persons from taking the tablet 10 by mistake I provide a blank 11 in the nature of a body which is bent to provide a series of pointed prongs 70 12, and a seat 13 adapted to receive the tablet, after which a plurality of the prongs 12 are bent around the edge of the tablet to secure the same on the body, with the remaining prongs projecting upwardly to 75 prick the fingers of a person accidentally endeavoring to take the tablet. Struck downwardly from the body are a series of auxiliary prongs 14 which are also pointed and are adapted to perform the same 80 function as the upstanding prongs of the body.

It will be understood that one of the devices is applied to each tablet and it will be apparent that if a person endeavors to take 85 the tablet in a solid form the guard must first be removed and furthermore the prongs on the guard will notify a person desiring to take a tablet, particularly in a darkened room or in the night season, that the tablet 90 is of a poisonous nature. If the tablet is to be dissolved in water or some other fluid, it will be apparent that the tablet with the guard thereon can be placed in the tumbler as a unit and the tablet will readily dissolve 95 therein, thus obviating the necessity of entirely removing the guard from the tablet in case the tablet is to be dissolved in the fluid.

Having thus described my invention, I 100 claim:

1. In combination with a tablet containing poison, a guard comprising a body provided with projections some of which constitute retaining members, others of which 105 constitute warning prongs.
2. In combination with a tablet containing poison, a guard comprising a body and

a plurality of prongs formed with said body, some of said prongs being bent around said tablet to securely hold said guard thereto.

3. In combination with a tablet containing poison, a guard comprising a body on which said tablet is seated and a plurality of projections formed with said body, some of said projections being bent around and over said tablet to securely hold said guard thereto and others of said projections extending from said body and constituting warning members.

4. In combination with a tablet containing poison, a guard comprising a body and a plurality of projections, said tablet being seated on said body and held thereto by some of said projections bent around and over said tablet, the others of said projections being bent to extend outwardly from said body and constituting warning members.

5. In combination with a tablet containing poison, a guard comprising a body and a plurality of projections formed with said

body, some of said projections being bent around said tablet to hold said guard thereto, others of said projections extending upwardly from the periphery of said body and constituting warning prongs and others of said projections extending downwardly from the face of said body and also constituting warning prongs.

6. In combination with a poisonous anti-septic tablet, a guard on which said tablet is seated, a plurality of prongs formed with said guard, some of said prongs being bent around tablet to hold said guard thereto and said guard being associated with said tablet to permit of the dissolution of said tablet in a fluid without first removing said guard.

In testimony whereof I affix my signature in presence of two witnesses.

CLARENCE J. DAWSON.
